[57] CLAIM

The ornamental design for a alternator injury preventor, as shown and described.

DESCRIPTION

FIG. 1 is a front elevational view of the alternator injury preventor showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top plan view thereof shown in use. The broken line showing is included for the purpose of illustrating environmental elements only and forms no part of the claimed design.

FIG. 1

FIG. 2

FIG. 3

FIG. 4

FIG. 5

FIG. 6

FIG. 7
